No. 700,803.

Patented May 27, 1902.

A. I. ORLANSKY.
PENCIL ATTACHMENT.

(Application filed Aug. 6, 1901.)

(No Model.)

UNITED STATES PATENT OFFICE.

ABRAHAM ISSAC ORLANSKY, OF BEAUFORT, SOUTH CAROLINA.

PENCIL ATTACHMENT.

SPECIFICATION forming part of Letters Patent No. 700,803, dated May 27, 1902.

Application filed August 6, 1901. Serial No. 71,046. (No model.)

To all whom it may concern:

Be it known that I, ABRAHAM ISSAC ORLANSKY, a citizen of the United States, and a resident of Beaufort, county of Beaufort, and 5 State of South Carolina, have invented certain new and useful Improvements in Pencil Attachments, of which the following is a specification, reference being had to the accompanying drawings, forming a part thereof, in 10 which similar letters of reference indicate corresponding parts.

This invention relates to pencil attachments, and has for its object to unite in one device the elements hereinafter specified and 15 claimed.

The nature of the invention will be fully understood from the following general description and the annexed drawings and will be subsequently pointed out in the claim.

20 Figure 1 of the accompanying drawings is a view of my newly-invented device, partly in vertical axial section and partly in elevation. Fig. 2 is a view of the inner tube and book, more fully hereinafter described. Fig. 25 3 is a transverse sectional view taken on the line $x'y$ of Fig. 1. Fig. 4 is a detail view, more fully hereinafter described. Fig. 5 is a modification.

A designates a hollow cylinder, which may 30 be of any convenient size and of any adaptable material. Each end of this cylinder is formed with a flange A', and its side is cleft with a longitudinal slot H. Within this hollow cylinder A is placed the tube B, comprising the parts b, b', and b². In this tube B is a sliding bar C, formed at its lower end with a hook c. A helical spring G actuates this bar. This spring G is attached by one end to the bar C and by the other to the interior 40 diaphragm g of the tube B. On the upper end of the bar C there is an index-point c', which moves in the slot a and over the scale a'. The flange b' of the tube B is adapted to rest upon the flange A' of the cylinder A, 45 and the end b is adapted to form a socket for holding and protecting the point end of the pencil P.

D designates a book, which may be composed of any adaptable material, as herein- 50 after more fully described, which may be fas-

tened to the tube B in any approved way, as with the rod k', as illustrated.

K designates bars or rods parallel to the cylinder A and parallel to each other. These rods are secured on either end in the flanges 55 A'. These rods may be of any desired number; but in the example of my invention here given I have illustrated ten. On each of these rods are placed ten balls or beads in such a way that they will slip freely on 60 the rods, each group of beads or balls on each rod being of a different color from all the other groups.

E designates a magnifying-glass, which is hinged to the flange A' at e and, being closed 65 up against the bottom of the cylinder A, is detachably held in position by the clasp e', which may be of any approved construction.

To use my invention as a book and reckoning device, the various parts are assembled, 70 as illustrated in Figs. 1 and 3 of the drawings, with the tube B and its accompanying mechanism in the cylinder A, the book D attached to the part b² of the tube B by the rod k' passing outwardly through the slot H and 75 extending beyond the outer surface of the cylinder A. Then the book may be used to be read or to enter accounts or memorandums. To do this writing, the pencil P may be taken out of the socket b. The balls or 80 beads O on the rods k may at the same time be used for calculating arithmetical problems, as in a common abacus. I prefer, however, to use these balls or beads as a decimal system for counting money. Thus let the 85 green group represent cents, the blue group represent dimes, the purple group represent dollars, and so on through the whole of the different-colored groups. Then by reckoning these values for each of the different 90 balls or beads in the different groups the operator has a money-abacus on which he can readily and quickly perform his calculations, as is commonly done on such a device. The book may be composed of a plurality of thin blank sheets for memorandums, or it may be printed with a lexicon or with 95 texts from the bible or any other matter that may be desired; but this matter may be printed in too small letters to be easily read 100.

with the naked eye. To obviate this difficulty, I have provided the magnifying-glass E, which, being released from the clasp e' and turned on the hinge e, may be used to read 5 the fine print. When the book is not being used, it may be wound up on the tube B in the cylinder A to make the device more portable.

To use my invention as a spring-balance, 10 the tube B is taken out of the cylinder A and the book unwound off of the part b², as illustrated in Fig. 2, so as not to be in the way of the index e' or to cover the scale a'. Then the operator grasping the socket b with one 15 hand can hang whatever he desires to weigh on the book c with the other hand; otherwise this part of the device is used as a common spring-balance. When the operator is done weighing, he rolls the book on the tube 20 B and returns tube, book, and all into the cylinder into the position heretofore described. It is contemplated to make this device as small as may be useful, so that it, with its pencil, can be readily carried in the 25 pocket.

In the modification illustrated by Fig. 4 4 1/2 the tube, as b³, carrying the pencil and weigh-

ing-scale, is in telescopic engagement with the tube B; otherwise the construction is the same as above described.

What I claim as my invention, and desire to secure by Letters Patent, is—

In a pencil attachment, the combination with the hollow cylinder A, formed with flanges A', and longitudinal slot H; of the 35 tube B, formed with the socket b, and flange b'; and having part b², the book D, and the rod k', securing said book to the part b², of the said tube B; and said book and said tube adapted and arranged, to be placed in said 40 hollow cylinder, with the flange b', resting on one of the flanges A', so that said book can be rolled in and unrolled out of said cylinder, through said slot H; substantially as shown and specified.

In testimony that I claim the foregoing as my invention I have signed my name, in presence of two witnesses, this 7th day of June, 1901:

ABRAHAM ISSAC ORLANSKY.

Witnesses:

J. H. ROZANSKY,
R. F. GREAVES.
